DROP WIRE COMPRESSOR FOR WARP DRAWING MACHINES

Russell P. Drake, Caledonia, Ill., assignor to
Barber-Colman Company, Rockford, Ill., a
corporation of Illinois

Application December 24, 1943, Serial No. 515,571

19 Claims. (Cl. 28—46)

The present invention pertains to warp drawing machines and its general object is to insure the release of drop wires for presentation successively to the drawing in needle of a drawing in machine.

Another object is to provide a practical mechanism for compressing and compacting a bank of drop wires on a release key in such a machine.

More particularly, it is an object to provide a mechanism for holding a backer against a bank of drop wires on a selectively operated release key in such manner that the backer is advanced in accordance with the variable release of the drop wires from the bank by the key, but in which the reaction of the compressed or compacted bank on the backer is utilized to limit the pressure on the bank by intermittently disabling the advancing mechanism for the backer.

Further objects and advantages of the invention will become apparent as the following description proceeds, taken in connection with the accompanying drawings in which:

Figure 1 is a side elevation of a mechanism embodying the invention.

Fig. 2 is a plan view of the apparatus of Fig. 1.

Fig. 3 is an enlarged sectional view taken substantially along the line 3—3 in Fig. 1.

Fig. 4 is a fragmentary sectional view taken substantially along the line 4—4 in Fig. 3.

Fig. 5 is a fragmentary perspective view of one of the banks of drop wires and its associated release key.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawings, the invention has been illustrated therein as embodied in a warp drawing machine and more particularly in a mechanism adapted to compact one or more banks of drop wires 10 on the corresponding release key or keys 11 of the machine. In the present instance two such release keys (see Fig. 2) have been shown and two corresponding banks of drop wires 10.

The release keys 11 are themselves of conventional form and comprise the usual fin 11a (see Fig. 5) spiraled with a long lead through one hundred and eighty degrees and fixed to the

forward end of a revoluble key shaft 11b. Each of the drop wires 10 is provided with a keyhole 12, such keyholes being staggered in successive drop wires in the bank in the usual manner so that upon each successive one-half revolution of the release key the next succeeding one of the bank of drop wires will be released. In the present instance the drop wires are slidably received on supporting rails 13 passing through longitudinal slots 14 in their upper portions, while the lower ends of the drop wires are slidably rested on supporting bars 15 (see Figs. 1 and 3). The rear ends of the release key shafts 11b are releasably secured in the usual drive chucks 16 provided for them in the warp drawing machine, the latter being revolutely mounted on the front face of a housing 17 into the rear face of which enter drive shafts 18 for revolving the release keys in unison.

In such an installation the problem, which the present invention solves, is to retain the bundles of drop wires 10 compacted under predetermined pressure on their respective release keys as the drop wires are released by the revolving keys. In the illustrative construction a plurality of backer fingers 19, one for each bundle (Figs. 1, 2 and 5) are arranged to press against the rear faces of the banks of drop wires in the area surrounding the keyholes 12. To accommodate such location of the backer fingers 19 they are longitudinally slotted for free reception of the key shafts 11b which pass through them. Such backer fingers 19 are slidably received in grooves 20 (Fig. 2) in the top of a bracket 21 having a cover plate 22 thereon which overlies the rear ends of the backer fingers.

An equalizing connection between the backer fingers 19 is constituted by a pinion 23 (Fig. 2) journaled on the top of the bracket 21 and meshing with rack teeth 24 on the opposed faces of the backer fingers. As the bracket 21 moves forward the backer fingers 19 engage the rear faces of the banks of drop wires and automatically adjust their relative positions, through the action of the pinion 23 and racks 24, to equalize the pressure applied to the bundles of drop wires.

The bracket 21 rises from and is rigid with a carriage 25 (Fig. 1) mounted by rollers 26 on a rail 27 for movement toward and away from the bundles of drop wires. The rail 27 constitutes a frame tie rod for the various parts of the machine herein shown and insofar as their action is concerned constitutes a stationary support, although the entire structure may be mounted on

rollers 28 to facilitate moving the mechanism into working position.

Power for advancing the backer carriage 25 is derived from a continuously revolving drive shaft 29 (Fig. 1) journaled in a bracket 29a on the rail 27. In brief, a pawl and ratchet mechanism designated generally as 30 is actuated by the shaft 29 and turns a pinion 31 meshed with a rack 32 for advancing the backer carriage 25 in accordance with the selective release of the drop wires incident to the operation of the release keys. As is hereinafter detailed, provision is made for disabling the drive mechanism whenever the pressure on the banks of drop wires 10 exceeds a predetermined value, herein determined by the tension of a contractile spring 33.

The pawl and ratchet mechanism 30 comprises a drive pawl 30a (Figs. 1 and 4), and a ratchet wheel 30b. The drive pawl 30a is carried by an eccentric 35 on a shaft 36. The latter shaft 36 in turn carries a helical gear 37 meshing with a similar gear 38 on the drive shaft 29. A tension spring 39 holds the drive pawl 30a in operative engagement with the ratchet wheel at all times, one end of the spring being anchored to the pawl and the other to an adjusting screw 39a carried by a bracket 40 bolted to the tie bar 27. The pawl 30a is thus oscillated by power derived from the drive shaft 29, advancing the ratchet wheel 30b step-by-step. The ratchet 30b is coaxial with the pinion 31 and is rigid therewith so that they revolve as a unit.

At its forward end the rack 32 is rigidly connected by an arm 41 with the backer carriage 25 so that if the pinion 31 were held against bodily movement in a direction fore and aft of the rack, the drive as so far described would result in a substantially continuous step-by-step advance of the backer carriage. Provision is made, however, for bodily motion of the pinion 31 in a direction rearwardly of the rack 32 (i. e., to the right as viewed in Fig. 1) when a predetermined pressure on the banks of drop wires 10 is reached, so as to disable the drive against further advance of the backer carriage 25 until the pressure falls below such predetermined value.

The pinion 31 and its attached ratchet 30b are floatingly supported for movement generally fore and aft of the rack 32 by a lever 42 (Figs. 1 and 4) which is pivoted intermediate its ends at 43 on the tie bar 27. The pinion and ratchet are freely journaled on the lower end of this lever 42. The contractile spring 33, heretofore noted, is anchored at its opposite ends to the upper end of the lever 42 and to an adjusting screw 43 in the upper portion of the bracket 40, thus urging the lever 42 to swing in a clockwise direction (as viewed in Fig. 1) against an adjustable stop 44. So long as the spring 33 holds the lever 42 against the stop, the rotation of the pinion 31 (in a counterclockwise direction as viewed in Fig. 1) will advance the rack 32. When the compression of the drop wires 10 becomes sufficiently great, however, to overcome the tension of the spring 33, the advance of the rack 32 stops and the continued rotation of the pinion 31 causes it to roll in a rearward direction along the rack (to the right as viewed in Fig. 1). Upon such movement of the pinion to the right, the ratchet 30b is disengaged from a coacting backup pawl 45, whereupon the drive for advancing the rack 32 is disabled and remains disabled until the drop wire compression diminishes sufficiently that the spring 33 can again pull the lever 42 over against the stop 44.

The holding or backup pawl 45 mentioned above (Figs. 1, 3 and 4) is pivoted on a stud 46 journaled eccentrically in a headed sleeve 46a (Figs. 3 and 4) for purposes of adjustment, the sleeve 5 being mounted in a block 46b suitably fastened to the bracket 29a. The pawl is urged toward the ratchet by a tension spring 47 anchored together with the spring 39 to the adjusting screw 39a in the lower end of the bracket 40, the springs 39 and 47 for the two pawls being disposed side by side. An adjustable stop 49 limits the movement of the backup pawl 45 so that the latter is engaged with the ratchet 30b only when the lever 42 supporting the latter is pulled over against its stop 44. Accordingly, the ratchet wheel is freed from the backup pawl whenever compression of the drop wires exceeds the limit determined by the spring 33, thereby disabling the ratchet drive at such time through disengagement of the backup pawl.

To facilitate withdrawal of the backer carriage 25, a hand lever 50 is constituted by an upward extension of the drive pawl 30a. Upon swinging this lever 50 clockwise (as viewed in Fig. 1) both of the pawls 30a and 45 are withdrawn from engagement with the ratchet, the backup pawl 45 having a laterally extending pin 51 thereon engageable by the rear edge of the drive pawl so that as the latter moves rearwardly it will pull the backup pawl with it.

The operation of the apparatus will in general be clear from the foregoing. By way of recapitulation it may be noted that the drop wires 10 are positioned on their supports 13, 15, the release keys 11 threaded therethrough in the usual manner, and the shafts of such release keys engaged in the chucks 16. To bring the backer fingers 19 into engagement with the respective banks of drop wires, the operator has only to grasp the carriage 25 and push it forward. During such advance the ratchet wheel 30b rides freely past the pawls without any necessity for tripping the ratchet mechanism. Having thus preliminarily positioned the carriage 25, the operator starts the power drive for the machine, whereupon the drive shaft 29 is set in motion and the ratchet mechanism 30 revolves the pinion 31 slowly, step-by-step, to advance the rack 32 and attached carriage 25, thereby compressing the banks of drop wires 10.

Whenever the compression of the banks of drop wires reaches the predetermined value determined by the tension of the regulating spring 33, further advance of the rack 32 ceases for the time being and the subsequent rotation of the pinion 31 by the drive pawl 30b causes it to roll rearwardly along the rack. The lever 42 thus swings away from its stop and the ratchet 30b is disengaged from its backup pawl 45 so that the ratchet drive is, in effect, disabled. As further drop wires are released from the banks, the resistance to advance of the rack 32 diminishes until the contractile spring 33 finally succeeds in pulling the lever 42 back against its stop 44, whereupon the ensuing rotation of the pinion 31 advances the rack 32 again. Such advance of the rack 32 continues, with intermittent interruptions, whenever the lever 42 leaves its stop 44, so that the force applied for advancing the carriage 25 is substantially uniform. The equalizer mechanism 23, 24 applies this force equally to the backer fingers 19 irrespective of the relative sizes of the banks of drop wires against which the backer fingers are pressed.

To withdraw the backer finger 19 at any time, the operator has only to grasp the lever 50 and swing it to disengage the pawls 30a, 45, whereupon the carriage 25 may be shoved to the rear without interference from the ratchet mechanism.

I claim as my invention:

1. In a warp drawing machine, the combination of a revoluble release key adapted to be threaded through a bank of drop wires and to release them one by one as it revolves, a backer shiftable to compress a bank of drop wires on the release key, power driven means for advancing said backer to compress the bank, and means operable in response to attainment of a predetermined pressure on the bank for disabling said drive means against further advance of said backer until such pressure again drops below said predetermined value.

2. In a warp drawing machine, the combination of a release key rotatable to release successive ones of a bank of drop wires compacted against the same, a backer shiftable to compress a bank of drop wires on the release key, a drive connection for advancing said backer including driving and driven toothed members meshed with each other, and biasing means for yieldably urging the driving member against bodily movement relative to the driven member to hold the same releasably in operative position for advance of the driven member.

3. In a warp drawing machine, the combination of a release key rotatable to release successive ones of a bank of drop wires compacted against the same, means including a rack for compacting a bank of drop wires against the release key upon longitudinal advance of the rack, a pinion meshed with said rack and having a ratchet rigid therewith, means floatingly supporting said pinion and ratchet for bodily movement fore and aft of the rack while retaining the pinion in mesh with the rack, a drive pawl engageable with said ratchet through the latter's range of bodily movement for revolving the ratchet and pinion in a direction to advance the rack when the pinion is held against bodily movement, means for actuating said drive pawl, a stop for limiting bodily movement of said ratchet and pinion in a direction forwardly of the rack, and biasing means for yieldably urging said ratchet and pinion into their limit position defined by said stop.

4. In a warp drawing machine, the combination of a release key rotatable to release successive ones of a bank of drop wires compacted against the same, means including a rack for compacting a bank of drop wires against the release key upon longitudinal advance of the rack, a pinion meshed with said rack and having a ratchet rigid therewith, means floatingly supporting said pinion and ratchet for bodily movement fore and aft of the rack while retaining the pinion in mesh with the rack, a drive pawl engageable with said ratchet through the latter's range of bodily movement for revolving the ratchet and pinion in a direction to advance the rack when the pinion is held against bodily movement, means for actuating said drive pawl, a stop for limiting bodily movement of said ratchet and pinion in a direction forwardly of the rack, biasing means for yieldably urging said ratchet and pinion into their limit position defined by said stop, and a backup pawl engageable with said ratchet to prevent reverse rotation of the same only when said ratchet and

pinion are in their limit position defined by said stop.

5. In a warp drawing machine, the combination of a release key rotatable to release successive ones of a bank of drop wires compacted against the same, means including a rack for compacting a bank of drop wires against the release key upon longitudinal advance of the rack, a pinion meshed with said rack and having a ratchet rigid therewith, a lever pivoted to swing fore and aft of the rack and having said ratchet and pinion journaled thereon for bodily movement of the same fore and aft of the rack upon swinging of the lever, a holder for shifting said lever manually, a drive pawl engageable with said ratchet throughout the latter's range of bodily movement for revolving the ratchet and pinion in a direction to advance the rack when the pinion is held against bodily movement, means for actuating said drive pawl, a stop for limiting bodily movement of said ratchet and pinion in a direction forwardly of the rack, and biasing means for yieldably urging said ratchet and pinion into their limit position defined by said stop.

6. In a warp drawing machine, the combination of a revoluble release key adapted to be threaded through a bank of drop wires and to release them one by one as it revolves, a backer shiftable to compress a bank of drop wires on the release key, means including a ratchet and a co-operating pawl for advancing said backer to compress the bank, and means operable in response to attainment of a predetermined pressure on the bank for disabling said pawl and ratchet against further advance of the backer.

7. In a warp drawing machine, the combination of a plurality of release keys disposed side by side and revoluble in unison to release drop wires in succession from banks compacted against respective ones thereof, individual backers for each of said banks, a backer advancing member, an equalizing connection between all of said backers and said member, drive means for advancing said member in a direction to compress the banks of drop wires, and means operable in response to a predetermined resistance to advance of said member for disabling said drive means.

8. In a warp drawing machine, the combination of a pair of release keys disposed side by side and revoluble in unison to release drop wires in succession from banks compacted against respective ones thereof, a carriage mounted for traversing movement toward and away from the rear sides of banks of drop wires on respective ones of said keys, a pair of backer fingers mounted on said carriage for longitudinal sliding movement into engagement with respective ones of the banks to compress the same, an equalizing connection between said fingers including a pinion journaled on the carriage disposed between and meshed with racks on the respective fingers, drive means for advancing said carriage toward the banks of drop wires, and means operable in response to a predetermined resistance to advance of said carriage for disabling said drive means.

9. In a warp drawing machine having means operative to release drop wires one at a time from a bank for presentation successively to a drawing in needle, a pressure device, a rack bar connected with said device to move it, and power driven means for advancing said bar to maintain pressure upon the bank comprising a drive pin-

ion meshing with said rack bar and a support for said pinion yieldable to render the pinion ineffective to move the rack bar.

10. In a warp drawing machine having means operative to release drop wires from a bank one at a time for presentation successively to a drawing in needle, a pressure device, a rack bar connected with said device to move it, and power driven means for advancing said bar to maintain pressure upon the bank comprising a drive pinion meshing with said rack bar, a ratchet disk connected with said pinion, and a driving pawl engageable with said disk.

11. In a warp drawing machine having means operative to release drop wires one at a time from a bank for presentation successively to the drawing in needle, a pressure device, a rack bar connected with said device to move it, and power driven means for advancing said bar to maintain pressure upon the bank, comprising a drive pinion meshing with said rack bar, a ratchet disk rigid with said pinion, a driving pawl engageable with said disk, a holding pawl also associated with said disk, and a support for said pinion and said disk yieldable to render the advance of the bar by the pinion ineffective, said holding pawl being also rendered ineffective as an incident to the yielding of such support.

12. In a warp drawing machine, a mechanism for releasing drop wires from a bank one at a time for presentation to a drawing in needle, a backer for said pack of drop wires, and power driven means acting positively to advance said backer but yieldable when the pressure on the backer exceeds a predetermined value to render said means ineffective to advance the backer.

13. In a warp drawing machine having a revoluble release key adapted to be threaded through a bank of drop wires and operative to release them one by one as the key revolves, a backer shiftable to compress a bank of drop wires on the release key, a power driven shaft, and means forming a one way driving connection between said shaft and said backer for advancing the same.

14. The combination with a backer shiftable

to compress a bank of drop wires or the like, a power driven shaft, and means forming a one way driving connection between said shaft and said backer for advancing the same, said connection including a member yieldable when the pressure upon the backer exceeds a predetermined value whereby to disable the connection.

15. The combination with a backer shiftable to compress a bank of drop wires or the like, power driven means for advancing said backer toward the bank, said means including driven and actuating elements relatively disengageable manually.

16. The combination with a backer shiftable to compress a bank of drop wires or the like, power driven means for advancing said backer toward the bank, said means including driven and actuating elements relatively yieldable automatically to interrupt the driving connection when the pressure upon the backer attains a predetermined value.

17. The combination of a backer shiftable to compress a bank of drop wires or the like, and means for advancing the backer including a ratchet operatively associated with the backer and a power driven actuating pawl engageable with said ratchet.

18. The combination of a backer shiftable to compress a bank of drop wires or the like, a pawl and ratchet drive for advancing said backer including driving and driven toothed members, and means supporting one of said members for automatic disengagement from the other member when the pressure upon said backer attains a predetermined value.

19. The combination of a backer for a bank of drop wires and the like, means for advancing the backer to compress the bank including a driven element operatively associated with the backer and a continuously driven actuator for said element, and means operable in response to the attainment of a predetermined pressure on the bank for disabling such actuator against further advance of the backer.

RUSSELL P. DRAKE.
